BOX STRAPPING MACHINE

Alvin L. Winkler, Chicago, Robert E. Hager, Park Forest, and Kjell A. Falck-Pedersen, Cicero, Ill., assignors to Acme Steel Company, Chicago, Ill., a corporation of Illinois.

Application April 26, 1952, Serial No. 284,634

37 Claims. (Cl. 100—25)

This invention relates to box strapping machines and its purpose is to provide an improved machine for applying a flexible binder, such as a flat metal strap, about a box or package, drawing the binder taut, cutting it off from the source of supply and then uniting its overlapping ends. The primary object of the invention is to provide an improved machine in which all of the operations just mentioned, except for an initial operation of extending the binder partially around the box or package, are performed automatically in proper sequence and timed relation without any attention on the part of the operator.

In the operation of the machine, the completion of one binding operation leaves a predetermined length of strap in a position such that it partially encircles a package when the package is placed in binding position. After placing the package in that position the operator pulls out the free end of the strap and completes the encirclement of the package with the free end of the strap in a position to be gripped by the mechanism, whereupon the automatic operations are initiated and the free end of the strap is gripped, the slack in the strap then taken up by reversing the strap feeding means, the strap then positively drawn taut to a predetermined degree by the movement of a strap gripping device engaging the supply portion of the strap, the supply portion then held by a stationary gripping device, the supply portion then cut off, a joint formed between the ends of the tensioned strap, and the strap and package then released from the gripping mechanism.

One difficulty with the operation of prior box strapping machines has been that the strap has generally been drawn taut about the box by pulling mechanism which depends upon the slipping of a clutch or the like to terminate the tensioning operation and it has been found that the strap is not thereby drawn taut to the same degree when applied to different boxes. It is one of the principal objects of the present invention to provide improved mechanism for positively gripping the strap and drawing it taut to substantially the same degree in successive operations on different boxes or packages. A further object of the invention is to provide improved means whereby any desired degree of tension, within a wide range, may be created with accuracy in the strap surrounding the package. Another object is to provide means for insuring the operation of the strap tensioning mechanism only after the slack in the strap encircling the package has been removed. Other objects relate to various features of construction and arrangement which will appear more fully hereinafter.

The nature of the invention will be understood from the following specification taken with the accompanying drawings in which one embodiment of the invention and a modification of a part thereof are illustrated. In the drawings,

Figure 1 shows a perspective view of a preferred embodiment of the invention;

Fig. 2 shows a perspective view of a box or package

Fig. 15 shows a sectional view taken on the line 15—15 of Fig. 14;

Fig. 16 shows a sectional view taken on the line 16—16 of Fig. 5;

Fig. 17 shows a sectional view taken on the line 17—17 of Fig. 16;

Fig. 18 is a sectional view similar to that of Fig. 16 showing the strap tensioning mechanism when it is in its extreme tensioning position;

Fig. 19 shows a partial sectional view taken on the line 19—19 of Fig. 18;

Fig. 20 shows a side elevation of the strap tensioning gripping dog and its associated parts at that time in the operating cycle when the strap tensioning mechanism is about to start its operation;

Fig. 21 is a view similar to that of Fig. 20 illustrating the relative positions of the parts a short interval after the strap tensioning operation has started;

Fig. 22 is a view similar to that of Fig. 21 illustrating the strap tensioning parts when they are in the elevated position corresponding to that shown in Fig. 16;

Fig. 23 shows the parts of the strap tensioning mechanism after the strap tensioning dog has gripped the strap and has started its downward movement as illustrated by dotted lines;

Fig. 24 shows the strap tensioning mechanism in its lowermost position after the strap has been drawn taut around the box or package;

Fig. 25 shows the parts of the strap tensioning mechanism illustrated in Fig. 24 after these parts have started to return to their normal upper positions;

Fig. 26 is a view similar to that of Fig. 16 showing a modified form of means for loading the strap tensioning mechanism;

Fig. 27 shows a top plan view of the modified mechanism illustrated in Fig. 26; and

Fig. 28 shows a schematic diagram of the electrical system by which various parts of the machine are operated and controlled.

As illustrated in the drawings, particularly in Fig. 1, the invention is embodied in a box strapping machine comprising a casing 30 which is made up of a sheet metal shell 31 surrounding an internal frame structure which supports the movable parts of the mechanism. This casing 30 is open at its top but is normally closed by a lid or cover 32 which is hinged at 33 on the casing so that it may be tilted upwardly to the position shown by dotted lines in order to gain access to the mechanism within the casing. The lid or cover 32 serves as a table on which the box strapping operations are carried on. For this purpose, the table is provided with a recess in which are mounted a series of rollers 34 extending for a considerable distance from one end of the table and, adjacent the other end, the table is recessed to accommodate a lesser number of rollers 35. All of these rollers project slightly above the top surface of the table and serve as conveyors over which the boxes or packages may be conveniently moved to and from the strapping position. Between the two series of rollers, there is mounted a welding device 36 which is adapted to unite the overlapping ends of a strap passed around the package. The table is provided with a groove 32a adapted to receive the strap which is passed around the package and, at the rear of the table, there is mounted a guide 37 having a vertical groove 37a therein which is adapted to receive the strap 40 when it is projected upwardly from the interior of the casing as shown in Fig. 1 and to permit the forward looping of this strap about the 75

box or package which is positioned over the welding device 36 when the binding operation is carried on. At the forward side of the table 32, there is provided a panel 41 on which are mounted a series of knobs 42, 43 and 44 for controlling the operation of various parts of the apparatus which are designated, respectively, by the numerals 450, 445 and 528 in Fig. 28. Beneath this panel, there are mounted switches for controlling the operating circuit including a switch 45 by which each cycle of operations may be initiated. At the bottom of the casing 31, there is mounted a foot pedal 46 adapted to be manipulated by the operator to control the feeding of the strap 40 from the interior of the casing.

The strap 40 is adapted to be drawn taut around a box or package, such as the box 50 shown in Fig. 2, and after it has been drawn taut and its supply portion cut off, the overlapping ends are secured together to form an interlocking joint preferably by means of spot welds as shown at 51 in Figs. 2 and 3. Only one strap is shown as being applied around the box or package but, by shifting the position of the box or package on the table 32, any desired number of straps might be applied around a single package.

Before proceeding with a detailed description of the structure of the apparatus, reference will be made to the diagrammatic views of Figs. 4a to 4h, inclusive, which illustrate the sequence of the various operations which are performed from the time that the package is placed over the welding device until it has been completely bound and removed from the table of the machine. In these figures, certain primary parts of the apparatus are illustrated in their operative relationship looking toward the left-hand end of the machine as viewed in Fig. 1. Referring to Fig. 4a, the strap 40 is drawn from a supply reel (not shown) around a guide wheel 54 between the dogs of a movable gripping device 55 and then around a feed wheel 56 which is power driven and with which the strap is maintained in contact by a guide wheel 57. The feed wheel 56 is adapted to feed the strap through a guide channel 58a formed in a front gripping dog 58 which is pivoted at 59 on the frame structure and which is provided with a series of teeth 58b adapted to cooperate with a stationary gripping plate 60 in gripping the strap after it has been passed around the package 50. From the passage 58a of the front gripping dog 58, the strap extends through the lower guide channel 61a of a strap guide 61 which is positioned beneath the welding device 36. The strap then extends above a rear gripping dog 62 which is pivoted at 63 on the frame structure and which is provided with a series of teeth 62b adapted to cooperate with a stationary gripping plate 64 located beneath the package 50. At the proper time, the rear gripping dog 62 is adapted to be moved upwardly to cooperate with the plate 64 in holding the supply portion of the strap after it has been drawn taut about the package.

At the conclusion of a strapping operation, the parts of the machine normally come to rest in the relative positions shown in Fig. 4a with the free end 40a of the strap curved upwardly and extending partially over the box 50 positioned on the table against the guide 37. In normal operation, a sufficient length of strap will extend upwardly over the box to permit it to be passed around the box by the operator but, if a sufficient length of strap does not extend in this manner, the operator may step on the foot pedal 46 and thereby actuate the feeding mechanism, including the feed wheel 56, to cause the required length of strap to be projected upwardly over the box. Assuming that the box has been placed in proper position on the table and that a sufficient length of strap is present, the operator then seizes this end of the strap and extends it forwardly and downwardly around the box until it extends between the forward gripping dog 58 and the stationary gripping plate 60 and into the upper channel 61b of the guide member 61.

This channel is closed at its end so that when the strap has been thrust inwardly to the extent permitted by the depth of the channel 61b, the box has been completely encircled and the parts are in readiness for the cycle of automatic operations which is initiated by closing the switch 45 beneath the panel 41 at the front of the machine.

When the switch 45 is closed, the front gripping dog 58 is moved upwardly from the position shown in Fig. 4b to the position shown in Fig. 4c so that the free end of the strap is then gripped and held against the stationary gripping plate 60 and at the same time the rear gripping dog 62 begins an upward movement from the position shown in Fig. 4b to an intermediate position shown in Fig. 4c. When the free end of the strap 40 has thus been gripped, the feeding mechanism is reversed so that the feed wheel 56 is then rotated in the direction shown by the arrow 65 in Fig. 4c with the result that the loop of strap extending around the box is contracted until all of the slack has been taken out of the strap and it lies in close contact with the box under moderate tension, as shown in Fig. 4d. At the conclusion of this slack take-up the movable gripping device 55 is actuated and its gripping dogs seize the strap beneath the feed wheel 56 and move downwardly to continue the pull on the strap as indicated by the arrow 66 in Fig. 4d.

In Fig. 4e the relative positions of the parts are illustrated at a somewhat later stage in the operation when the movable gripping device 55 has moved downwardly to a further extent and the rear gripping dog 62 has moved still further in an upward direction so that an arm 62a on the free end of this dog extends upwardly at the side of the supply portion of the strap 40 to guide the strap and keep it in alignment with the free end of the strap which is then held by the front gripping dog 58. At this stage, the welding head 67, which has previously occupied its lowermost position, begins an upward movement from the lower position which is illustrated by dotted lines. At this stage the strap shearing blades 68 have been moved to a position where they embrace the supply portion of the strap somewhat forwardly from the position occupied by the welding device 36. In Fig. 4f, the operation has continued to the point where the strap has been drawn taut around the package with a predetermined tension in it and the rear gripping dog 62 has moved upwardly to the point where it grips the supply portion of the strap against the plate 64 and the shearing blades 68 have been actuated to cut off the strap, leaving two ends of the strap overlapping beneath the contacts of the welding device 36. The welding head 67 then moves upwardly from the position shown in Fig. 4f to the position shown in Fig. 4g and is actuated to weld the overlapping ends of the strap together to form the type of joint which is illustrated in Figs. 2 and 3. While this welding operation is going on, the movable gripping dogs are moved out of engagement with the supply portion of the strap beneath the feed wheel 56 and, the box having been completely bound, an ejecting device 69 is then actuated to engage the strap and move it out of engagement with the gripping plates 60 and 64 at the same time that the gripping dogs 58 and 62 are moved downwardly to the position shown in Fig. 4h. At the same time, the welding head 67 is moved downwardly from the position shown by dotted lines in Fig. 4h to the position shown by full lines so that the parts are then in readiness for a new binding operation except for the final actuation of the feed wheel 56 which then takes place to project a length of strap through the guide channel 61a of the guide 61 and upwardly through the groove 37a of the guide 37 so that it then will curve over the welding device 56 in readiness for a new strapping operation.

Before proceeding with a detailed description of the operating mechanism of the machine, reference will be made to the frame structure which supports the outer

shell of the cabinet 31 shown in Fig. 1, as well as the various parts of the operating mechanism. As shown particularly in Figs. 5, 6 and 7, this frame structure comprises four upright frame members 75, 76, 77 and 78 which extend vertically at the corners of the cabinet and are provided at their lower ends with horizontally extending flanges 79 provided with apertures 79a adapted to be engaged by studs or bolts for the purpose of securing the cabinet to the floor or other support. Adjacent their lower ends, the vertical frame members 75 and 76 are connected by a horizontal frame member 80 of angle bar form and, at the rear of the machine, the lower ends of the vertical frame members 77 and 78 are similarly connected by a horizontal frame member 81 of angle bar cross section which has its top horizontal flange in the same plane as the top flange of the frame member 80. These frame members 80 and 81 are connected by two angle bars 82 (see Fig. 5) on which there is mounted a plate 83 arranged to serve as a support for an electric motor 85 by which most of the movable parts of the machine are actuated.

Some distance above the horizontal frame members 80 and 81 the vertical frame members 75 and 76 are connected by a horizontal channel-shaped frame member 86 which has its flange directed outwardly and which is arranged in the same horizontal plane as the corresponding channel-shaped frame member 87 which extends between the upright frame members 77 and 78 at the rear of the machine. The top end of the frame member 75 is connected to the top end of the frame member 77 by a bar 88 and the top end of the upright frame member 76 is similarly connected to the top end of the frame member 78 by an angle bar 89.

Adjacent the left-hand end of the machine, as viewed in Fig. 5, the front horizontal frame member 86 is connected to the rear horizontal frame member 87 by two parallel channel-shaped members 90 which have their ends welded to the inner vertical faces of the members 86 and 87. The upper horizontal flanges of these frame members 90 have welded thereto four blocks 91 to which are secured by bolts 92 the base flanges of a metal casting 93 which serves as a supporting frame for most of the movable parts of the mechanism. Toward the right-hand end of the machine a pair of angle bars 94 are welded at their rear ends to the horizontal frame member 87 and these angle bars are supported toward their forward ends by upright frame members 95 which are welded thereto at their upper ends and which are welded at their lower ends of the plate 83 by which the motor 85 is supported. The bars 94 serve as supports for an electric transformer 100 which is supported above the bars 94 by four bolts 101 which are threaded at both ends for engagement with apertures in the frame of the transformer and in the bars 94 and which are engaged by a series of nuts 102.

Somewhat to the right of its middle point, the front horizontal frame member 86 has welded thereto an upright frame member 103 which is welded at its upper end to a horizontal frame member 104 secured at its right-hand end to the upright frame member 76. A plate 105 is welded to the frame member 104 to extend downwardly therefrom and this plate serves as a support for a rotary switch 106 which is connected in the electric operating circuit as hereinafter described. At the rear of the machine, the horizontal frame member 87 has secured thereto an upstanding frame member 107 which is similar to the frame member 103 and which is secured at its upper end to a horizontal frame member 108 extending to the right-hand end of the machine where it is welded to the upright frame member 78.

At the lower left-hand end of the frame structure, the frame member 75 is connected to the upright frame member 77 by means of a horizontal frame member 109 which has bolted to the forward end thereof a horizontal plate 110 arranged to serve as a support for a hy-

draulic pump 111 which is arranged to circulate under pressure the hydraulic fluid which is employed in the operation of the machine. On the other side of the frame member 109, there is mounted a hydraulic cylinder 112 which serves in conjunction with the pump 111 to regulate the tension set up in the strap 40 by the tensioning mechanism 55, as more fully described hereinafter. At the left-hand rear corner of the cabinet, adjacent the upright frame member 77, there is mounted a hydraulic accumulator 114 which is held in place by an encircling strap 114a which is attached at one end to the frame member 77 by a stud 116 and secured at the other end to a bracket 117 which is welded to the horizontal frame member 87. The lower end of the accumulator 114 communicates with a T-connection 115 from which one conduit 118 extends to a port at the upper end of the pump 111 while another conduit 119 extends to the end of the cylinder 112 which is adjacent the forward side of the machine.

A cam shaft 120, extending longitudinally of the machine, is journaled in bearings mounted in the cast metal frame 93 and this cam shaft has fixed thereon a series of cams 121, 122, 123 and 124, shown particularly in Fig. 9, which serve to control various parts of the operating mechanism as the cam shaft is rotated. The cam 121 operates in conjunction with the control of the tension mechanism 55, the cam 122 serves to move the welding head 67 to and from its operating position and also to actuate the forward gripping dog 58, the cam 123 operates to actuate the strap ejector 69 and the rear gripping dog 62 as well as the strap end guide 61, and the cam 124 controls the actuation of the shearing mechanism 68.

The cam shaft 120 is driven by a belt 125 extending around a pulley 126 on the shaft 127 of the motor 85 and also around a pulley 128 which is rotatably mounted on the cam shaft as shown in Figs. 6 and 9. The pulleys 126 and 128 are provided with a pair of V-shaped grooves which are engaged by the corresponding projections of V-shaped cross section which are formed on the inner side of the belt 125. At the left-hand end of the cam shaft, as viewed in Figs. 7 and 9, the shaft has fixed thereon a sprocket gear 129 which meshes with a chain 130 having a driving engagement with a sprocket pinion 131 fixed on a feed shaft 135 which is journaled at one end in a ball bearing unit 136 mounted in a bearing member 137 attached to the frame 93, and at its other end in an overrunning clutch 138 mounted in a bracket 139 of L-shaped form which is secured to the frame 93 as shown particularly in Fig. 7. The overrunning clutch 138 permits rotation of the shaft 135 in one direction but prevents rotation in the opposite direction. At an intermediate point the feed shaft 135 has mounted thereon the feed wheel 56 by which the strap 40 is fed from the source of supply, this mounting being effected by an elongated hub portion 56a, shown in Fig. 9, which is journaled in ball bearing units 140 and 141 mounted in the frame 93. The feed wheel 56 has a gear 143 mounted on its hub and secured to the side thereof, as shown in Fig. 9, and this gear meshes with a pinion 144 secured upon a countershaft 145 which is journaled in ball bearing units 146 and 147 mounted in the frame 93 and in the bracket 139, respectively. Thus, when the shaft 145 is actuated the pinion 144 drives the gear 143 and thereby actuates the strap feed wheel 56.

The cam shaft 120 also has rotatably mounted thereon a sprocket wheel 148 which rotates with the pulley 128 and meshes with sprocket belt 149 extending around a sprocket wheel 150 mounted to revolve about the feed shaft 135 and also about a sprocket pulley 151 which is rotatably mounted upon the countershaft 145. When the motor 85 is operated to drive the pulley 128, the connected sprocket pulley 148 is simultaneously rotated to drive the belt 149 so that both of the sprocket pulleys 148 and 151 are thereby actuated. Means are provided for connecting these sprocket pulleys to the shafts 135 and 75

145, respectively, in order to control the operation of the feed wheel 56 and the actuation of the cam shaft 120 on which the cams 121, 122, 123 and 124 are mounted.

The sprocket pulley 151 has a long hub 151a which is mounted to revolve about the shaft 145 on ball bearing units 152 and 153 which are positioned against shoulders on an intermediate part of the shaft as shown in Fig. 9. One end of the hub 151a has secured thereon a ring 155 which is secured by studs 156, metal ring 157, and pins 158 to the casing of a ring-shaped electromagnet 160 which revolves with the sprocket gear 151 about the shaft. Adjacent to the magnet 160 which forms a part of an electromagnet clutch, there is mounted a complementary ring 161 which is secured upon the countershaft 145 by means of a key 162. This ring 161 is provided with an annular series of apertures 161a in which there are slidably mounted plungers 163 having enlarged heads which are fastened to an annular metallic ring 165 made up of a member 165a of channel form and a connected flat disk 165b which is adapted to coat with the radial face of the clutch magnet 160. Each of the plungers 163 is provided with a spring 164 which reacts between the ring 161 and the annular metallic ring 165 to urge it against the clutch magnet 160. Electric current is supplied to the clutch magnet 160 by means of slip rings 166 and wires 158 which are mounted upon the ring 155 and separated from each other by an annular insulating member 167. Brushes engaging these slip rings are connected in the electric circuit hereinafter described and when the clutch magnet 160 is energized, the magnetizable ring 165 is attracted and held by the magnet so that the magnet and the sprocket gear 151 then rotate the clutch member 161 with the result that the countershaft 145 is thereby actuated to operate the pinion 144 and thereby drive the feed wheel 56 through the gear 143 so that the metal strap 40 is thereby fed through the guide member 37 to the strapping position above the table 32 as heretofore described.

There is also mounted around the countershaft 145 an annular electromagnet 170 which is secured by a metal ring 171 and studs 172 to the bracket 139 carried by the frame 93. Since the magnet 170 is stationary, connections to its electric winding may be made through stationary terminal posts in the usual manner. The electromagnet 170, when energized, attracts a metallic ring 173 made up of a flat ring 173a adapted to contact with the end face of the casing of the magnet 170 and another member 173b of channel-shaped cross section to which there is secured the enlarged ends of another series of plungers 174 which are slidably mounted in certain of the apertures 161a formed in the disk 161. The plungers 174 are arranged alternately with the plungers 163 around the outer portion of the disk 161 and coil springs 175 normally press the ring 173 into engagement with the end face of the clutch magnet 160 which serves as a brake to arrest the rotation of the shaft 145 when it is energized. When the shaft 145 is rotating, the plate 173a is pressed against the end face of the magnet by the springs 175 but, upon deenergization of the clutch magnet 160, the brake magnet 170 is energized by the operation of the electric circuit hereinafter described so that the brake ring 173 is thereby attracted and the shaft 145 is brought to rest. The connections of the electric circuit are such that the two magnets 160 and 170 cannot be energized at the same time. At the right-hand end of the shaft 145, as viewed in Fig. 9, a gear 176 is fixed to rotate with the shaft and this gear meshes with another gear 177 mounted upon the shaft of the rotary switch 106, as shown in Fig. 5, so that this switch is operated to control certain parts of the electric control circuit each time that the countershaft 145 is rotated.

The pulley 128 and the sprocket pulley 148, which are rotated continuously when the motor 85 is in operation, operate through the belt 149 to effect a simultaneous rotation of the gear 150 which has a long hub 150a

mounted to revolve in ball bearing units 178 about an intermediate part of the feed shaft 135 and the rotation of this sprocket gear 150 is made use of for effecting a reverse rotation of the feed wheel 56 when it is desired to take up the slack in the strap which has been extended around the package as previously described. The rotation of the gear 150 is also utilized to effect a rotation of the feed shaft 135, independently of the feed wheel 56, thereby driving the cam shaft 120 through the sprocket gears 129 and 131 and the sprocket chain 130. For the latter purpose, there is provided a magnetic clutch for connecting the rotating gear 150 directly with the right-hand portion of the feed shaft 135, as viewed in Fig. 9. This clutch comprises a ring magnet 180 which is secured by a ring 181 and studs 182 to a ring 184 which is secured on the end of the hub portion 150a of the sprocket gear 150. The electric winding of the magnet 180 is adapted to be supplied with electric current through slip rings 185 which are secured on the ring 184 and which are separated from each other by an annular insulating member 186. A clutch disk 188 is secured upon the shaft 135 by a key 189 and this disk is provided with an annular series of cylindrical apertures 188a, extending parallel to the axis of the shaft 135, in which there are mounted the reduced stems of a plurality of plungers 190 secured at their large ends to a magnetizable ring 191 which is similar in construction to the ring 165 and which is pressed against the end face of the magnet 180 by a series of coil springs 192. When the clutch magnet 180 is energized by current supplied through the slip rings 185 and wires 183, the armature ring 191 is held in fixed relation to the electromagnet so that the sprocket gear 150 then operates through the magnet to drive the clutch disk 188 and thereby rotate the shaft 135 with a resulting rotation of the cam shaft 120 on which the various control cams 121, 122, 123 and 124 are fixed.

When it is desired to arrest the rotation of the feed shaft 135 and the cam shaft 120, the clutch disk 188 is stopped by a ring magnet 195 which is secured by studs 196 and an annular ring 197 to the stationary bracket 139. This ring magnet 195 which serves as a part of a brake is adapted to actuate a brake ring 198 which is similar in construction to the brake rings 165 and 191 and which is moved into contact with the end face of the brake magnet 195 by means of a series of plungers 199 which are mounted in alternate apertures 188a formed in the clutch disk 188 and actuated by coil springs 200 which are mounted upon their large ends between the disk 188 and the ring 198. When the electromagnet 195 is energized by electric current supplied through stationary terminal posts (not shown), the magnetic armature 198 is held in fixed relation to the magnet, thereby arresting the rotation of the shaft 135 and stopping the rotation of the cams 121, 122, 123 and 124. The connections of the electric circuit are such that the two magnets 180 and 195 may not be energized simultaneously.

The left-hand end of the hub portion 150a of the sprocket gear 150, as viewed in Fig. 9, has fixed thereon an annular collar 201 which is secured by studs 202, an annular ring 203, and to the casing of an annular clutch magnet 205 adapted to revolve with the sprocket gear 150 about the shaft 135. A clutch disk 206 is mounted adjacent to the magnet 205 about the extremity of the hub portion of the feed wheel 56 and a projecting portion of the hub of the disk 206 is supported by a ball bearing unit 207 mounted upon the shaft 135. As in the case of the clutches previously described, the clutch member 206 has an annular series of apertures 206a in which there are mounted the stems of a series of plungers 208 each of which is fixed to the annular channel-shaped portion of an armature ring 209 seated against the end face of the magnet 205. A series of coil springs 210 are mounted upon the plungers 208 and serve to maintain the armature ring 209 in contact with the magnet. When the

magnet is energized by current supplied thereto from slip rings 211 and wires 204 mounted upon the collar 201 on opposite sides of an insulating ring 212, the armature ring 209 is held in fixed relationship to the clutch magnet 205 so that the clutch disk 206 is thereby rotated and the feed wheel is rotated in the reverse direction so that it takes up the slack in the strap 40 extending around the package 50 and draws it in from the condition shown in Fig. 4c to the condition shown in Fig. 4d.

Having described the mechanism for feeding the strap to the position where the package is to be bound and for taking up the slack in the strap which has been extended around the package, as well as the mechanism for actuating the cam shaft and the various cams mounted thereon, a more detailed description will now be given of the parts which are actuated or controlled by these cams. Referring particularly to Figs. 6, 7 and 8, the front gripping dog 58, previously referred to in connection with Figs. 4a to 4h, inclusive, is mounted on a pivot 59 fixed in the frame 93 and it has mounted on the rear end thereof a detachable gripping block provided with the teeth 58b previously referred to which are adapted to cooperate with the stationary gripping plate 60 in holding the strap after it has been looped about the package.

The strap coming from the feed wheel 56 extends through the slot 58a formed in the gripping dog and after the end of the strap has been moved into the channel 61b of the guide member 61, as previously described, the gripping dog 58 is moved upwardly about its pivot 59 to grip the strap. This pivotal movement is effected through a link 215 (see Fig. 8) which comprises a member 216 pivoted at 217 to the under side of the gripping dog 58 and having a stem 216a which has a telescoping engagement with a sleeve 218a formed as a part of a member 218 which is pivoted at 219 on a bell crank lever 220. A coil spring 221 surrounds the parts 216a and 218a and abuts at its ends against one of the nuts 222 adjustably mounted upon the threaded portion of the member 216 and a collar 218b which is formed on the member 218. The bell crank lever 220 is pivoted at 223 on a part of the frame 93 and the lower arm of this lever has pivotally mounted thereon a roller 225 which coats with the irregular peripheral surface of the cam 122 mounted on the shaft 120. When the roller 225 is in engagement with the portion 122a of the cam which is of smaller radius, the gripping dog 58 will be in the retracted position shown in Fig. 8 but when the cam shaft 120 has rotated to a point where the roller 225 engages the high part 122b of the cam, the gripping dog is moved upwardly so that the serrations 58b thereof engage the strap and hold it stationary against the plate 60. At this time, the spring 221 is adapted to yield so that a resilient pressure will be exerted upon the strap and, in order to regulate the degree of this pressure, the nuts 222 may be adjusted on the member 216. When the cam again reaches the point where the roller 225 is adapted to be moved into engagement with a part of the cam of lesser radius, the gripping dog 58 is retracted to the position shown in Fig. 8 by the coil spring 226 which is connected to the pivot pin 219 and to another pin 227 mounted in a stationary position on the frame 93 or other stationary part of the structure.

After the strap 40 has been passed around the package and moved into the position shown in Fig. 4b with its extremity engaging the channel 61b of the guide member 61, it is desirable to prevent an accidental retraction of the strap end before it is gripped by the dog 58 and, for this purpose, the gripping dog is provided on its opposite sides with upwardly extending slots 58c in which are mounted leaf springs 228 secured in place by pins 229 mounted on the sides of the gripping dog beneath the slots. These springs 228 are provided with teeth 228a which are adapted to engage the edges of the strap as it occupies the groove 58d in the upper part of the gripping dog, whereby any tendency of the strap

end to be retracted from the guide channel 61b is resisted by the engagement of the teeth 228a with the edges of the strap.

The rear gripping dog 62, which is adapted to engage the supply portion of the strap after it has been extended around the package and into engagement with the guide channel 61b, is pivoted at 63 on the frame member 93 and is provided at its forward end with a detachable block carrying the teeth or serrations 62b, previously referred to, which are adapted to engage the under side of the strap to hold it against the gripping plate 64. The guide finger 62a which is adapted to engage the edge of the supply portion of the strap to hold it in alignment with the free end of the strap is formed as a detachable member which is secured to the body of the gripping dog 62 by the pin 230 which also secures the block carrying the serrations 62b. The gripping dog 62 is adapted to be moved to and from the strap gripping position by means of a link 231 which is generally similar to the link 215 previously described, comprising an upper member 232 which is pivoted at 233 to the forward portion of the gripping dog 62. The member 232 has a downwardly extending sleeve 232a in which there is slidably mounted a pin 234a formed as a part of a member 234 which is pivoted at 235 to a bell crank lever 236. A pair of nuts 237 are mounted upon the lower threaded portion of the member 234 and a coil spring 238 extends between the upper nut and a collar 232b which is formed as a part of the member 232. This coil spring is adapted to maintain a predetermined separation of the members 232 and 234 and the extent to which these members may be moved toward each other is limited by a pin 239 fixed in the sleeve 232a and engaging a slot 234c which is formed in the stem 234a. There is a pin and slot connection (not shown) between the parts 216a and 218a to limit their separation in the manner hereinafter described in connection with the link 231. The bell crank lever 236 has a lower arm 236a upon which there is rotatably mounted a roller 240 adapted to travel upon the peripheral surface of the cam 123. A coil spring 241 extends between the pivot pin 235 and a stationary part of the frame 93 and this spring maintains the roller 240 in contact with the peripheral surface of the cam 123 and moves the gripping dog 62 to the retracted position when the cam shaft 120 rotates to the point where the roller 240 engages that portion 123a of the cam surface which is of smaller radius. As the cam shaft rotates and the roller moves into engagement with the part 123b of the cam surface which is of larger radius, the bell crank lever 236 is actuated to move the gripping dog 62 upwardly so that the teeth 62b then coat with the under side of the supply portion of the strap and hold it against the stationary gripping plate 64 with a resilient pressure which is provided by the inclusion of the spring 238 in the link 231.

The cam 123 which actuates the gripping dog 62 also operates the strap guide 61 and the strap ejector 69 by the mechanism which is illustrated particularly in Figs. 14 and 15. The strap ejector 69 is slidably mounted in a guideway 243 formed in the upper part of the frame 93 and is provided with a projecting extremity 69a which is adapted to engage the edge of the strap bound around the package, after the binding operation has been completed, for the purpose of moving the strap out of engagement with the stationary gripping plates 60 and 64 and the intervening parts of the welding head 36. This member 69 is provided at its inner end with depending arms 69b forming a slot which is slidably engaged by a block 244 pivotally mounted on the upper end of the long arm 245a of a bell crank lever 245. This lever is pivoted on a rod 246 mounted in ears 247 extending upwardly from a part of the frame 93 and the short arm 245b of this lever is pivotally connected by a pin 248 to a yoke-shaped member 249 mounted to ride upon the upper end of a plunger 250 arranged to slide vertically in a guideway 251 formed in the frame 93. The lower end

of this plunger 251 carries a roller 252 which engages a groove 123c formed in the side of the cam 123. Thus, as the cam 123 revolves with the cam shaft 120, the lever 245 is actuated to reciprocate the strap ejector 69 so that, at the proper time, when the roller 252 engages the peak 123d of the slot 123c, the extremity 69a of the ejector is thrust forwardly to engage the bound strap and thus release the strap and the package from the stationary gripping plates 60 and 64 and from other parts of the mechanism.

The strap guide 61, having the lower guideway 61a and the upper guideway 61b, is carried by the upwardly extending arm 255a of a lever 255 which is provided at its lower end with arms 255b which are rotatably mounted on pins 255c mounted in the portion 305 of the casting 93. A crank arm 257 is secured to one of the arms 255b and extends upwardly therefrom with its upper end pivotally connected at 258 to a rod 259 which slidably extends through a guide member 260 pivoted at 261 on the long arm 245a of the lever 245. A coil spring 262 is mounted on the rod 259 between the guide member 260 and a nut 263 which threadedly engages the end of the rod, as shown in Fig. 15. When the long arm 245a of the bell crank lever 245 is retracted to the position shown in Fig. 15, the rod 259 is actuated to swing the bell crank lever 255 upwardly from the position shown by dotted lines to the position shown by full lines wherein it is adapted to receive the supply portion of the strap through the guide channel 61a and to receive the extremity of the strap in the guide channel 61b which is closed at one end.

As shown in Fig. 6, the guide channels referred to are formed by three members spaced apart including a lower member 265, an intermediate member 266, and an upper member 267. The right-hand ends of the members 266 and 267 are flared away from each other so that the channel 61b will more readily receive the free end of the strap which is limited in its movement into the channel by the small block 269 which closes the end of the channel. Similarly, the right-hand end of the lower member 265 is inclined downwardly to guide the supply portion of the strap into this channel as it moves from the feed wheel 56.

After the slack in the strap extending around the package has been taken up by reversing the feeding mechanism in the manner heretofore described and after the strap has been drawn taut by the tensioning device 55 described hereinafter, the strap is gripped by the rear gripping dog 62 as previously explained, and the supply portion of the strap is then cut off by the shearing device 68 which is shown particularly in Figs. 10, 11 and 12. This shearing device comprises two members 270 and 271, the former of which is mounted to slide in a horizontal guideway 272 formed in the upper part of the casting 93, as shown in Figs. 11 and 12. The members 270 and 271 are provided with shearing blades 270a and 271a which are adapted to have relative movement after these members have been moved from the position shown in Fig. 11 to a position where the blades embrace the supply portion of the strap. A rectangular block 273 is pivotally connected to the rear end of the member 270 by means of a pin 274 and this block has a sliding engagement with a longitudinal slot 275a formed in the upper arm of a bell crank lever 276 which is pivoted at 277 on the shaft 246 secured in the ears 247 extending upwardly from a portion of the casting 93. The lower arm 276b of the bell crank lever is engaged at its end by a pivot pin 280 which extends through an elongated slot formed in the upper end of a plunger 281 of rectangular cross section which is slidably mounted in a guideway 282 of corresponding cross section formed in the casting 93. The lower end of the plunger 281 has a roller 283 rotatably mounted thereon and this roller is arranged to travel in a cam slot 124a formed in the side of the cam 124. As the cam rotates with the cam shaft

the axis of the shaft in that part of the cam groove 124a which has the smaller radius and, during this time, the members 270 and 271 which are pivoted together by the bolt 285 occupy the retracted positions shown in Fig. 11. At the proper time in the strapping cycle, the roller 283 passes through the portion 124b of the cam slot which is of larger radius and the plunger 281 then actuates the bell crank lever 276 to move the members 270 and 271 forwardly from the position shown in Fig. 11 to the position where the shearing blades 270a and 271a embrace the supply portion of the strap, whereupon a relative pivotal movement of the member 271 is effected with respect to the member 270 about the pivot 285, thereby shearing off the strap as the blades move to the final shearing position shown in Fig. 12.

This pivotal movement of the member 271 is effected by a rod 286 which is pivoted at 287 to the rear end thereof and which is attached at its lower end by a ball and socket joint 287a to one arm of a bell crank lever 288 pivoted at 289 between two ears 290 carried by the casting 93. The lower arm 288a of this bell crank lever has mounted thereon a roller 291 which is arranged to travel on the peripheral surface 124c of the cam 124. A coil spring 292 is mounted around the hub of the bell crank lever 288 with one end thereof engaging a lug 288b formed on the lever and with the other end thereof hooked around a shoulder on the casting 93 so that this spring operates to maintain the roller 291 in contact with the cam. As the cam shaft 120 rotates with the roller 291 engaging that portion of the outer peripheral surface of the cam which is of constant and lesser radius, the member 271 remains stationary with the shearing blades separated as shown in Fig. 11. After the shearing blades have been advanced by the actuation of the bell crank lever 276, as heretofore described, the roller 291 engages the hump 124d of the cam 124 and the rod 286 is then pulled downwardly to effect a pivotal movement of the member 271 about the pivot 285 so that the blade 271a moves upwardly to shear the strap, whereupon the parts are in readiness for the formation of a joint between the overlapping ends of the strap as heretofore referred to.

In the embodiment illustrated the joint between the overlapping strap ends is formed by spot welding through the use of the welding device 36, illustrated particularly in Fig. 8, which comprises welding points 295 and 296 connected in the electric circuit and carried by supports 297 and 298, respectively. These supports are positioned between the stationary gripping plates 60 and 64 and the welding points project slightly below the horizontal plates of the supports so that they are adapted to cooperate with a movable welding head 300 to form spot welds uniting the overlapping strap ends when the welding head is moved upwardly from the position shown in Fig. 8 to engage the the under side of the lowermost strap end. This welding head is a channel-shaped member of sufficient length to extend slightly beyond the range covered by the spacing of the welding points and it is supported by a pin 301 which engages an arcuate groove in the under side of the top wall 300a of the head and a corresponding groove in the upper end of a stem 302a formed on the upper end of a plunger 302. The supporting pin 301 is of substantial diameter and the welding head is permitted to rock upon it to a limited extent so that it will conform to the position of the lowermost strap end and cause the strap ends to be thrust upwardly against the welding contacts when the welding head is elevated. For the purpose of holding the pin 301 in its proper position, it is provided with extremities 301a of small diameter which engage apertures in brackets, not shown, which are secured by screws to a plate 303 extending around the stem 302a and to the top plate of a skirt member 304 which is attached to the upper end of the plunger 302 with its annular flange extending downwardly around the upper end of a cylinder 305 formed on the casting 93 which has a tubular bore in which the

plunger 302 is slidably mounted. A packing ring 306 is carried by the upper end of the cylinder 305 to coat with the outer surface of the plunger 302, thereby forming a tight connection between these parts, and this joint 5 in conjunction with the skirt member 304 is adapted to protect the movable parts of this mechanism from dirt and from the flash which results from the welding operation.

The plunger 302 is made up of two complementary parts including an upper member 302b which carries the stem 302a and a lower member 302c which is slidably mounted in the lower part of the cylinder and which carries a stem 302d arranged to slide in a tubular bore formed in the upper part 302b. A coil spring 308 is 10 mounted in sockets formed in the opposed ends of the complementary plunger members 302b and 302c and tends normally to separate them longitudinally. The extent of this separation is limited by a pin 309 carried by the part 302a and engaging a vertically elongated slot 20 302e formed in the stem 302d. When the plunger 302 is moved upwardly to cause the welding head 300 to press the strap ends upwardly against the welding contacts 295 and 296, the spring 308 permits the strap ends to be pressed together and into engagement with the 25 contacts with a yielding pressure, thereby insuring a thorough welding operation.

The actuation of the plunger 302 is effected by a roller 310 which is rotatably mounted on a pin 311 carried at its lower end. This roller engages a cam groove 122c 30 formed in the side of the cam 122 by which the forward gripping dog 58 is actuated. This cam slot 122c is of irregular contour and is so formed that, at the proper time in the cycle of operations, after the strap has been drawn taut around the package and its ends cut off, 35 the plunger 302 will be thrust upwardly to move the welding heat 300 into operating engagement with the lower strap end. A key 312 carried at one side of the lower part of the plunger 302 slidably engages a keyway in the cylinder 305 to prevent rotation of the plunger during 40 its reciprocatory movement.

Referring now to the means for feeding the strap to the strapping table and for withdrawing the strap to take up the slack, the feed wheel 56 rotates with the gear 143, as previously described, and the strap is maintained 45 in contact with the feed wheel by the guide wheel 57 which is arranged to rotate positively with the feed wheel through a gear 315 which is attached to the side of the guide wheel and arranged to mesh with the gear 143. The guide wheel and the gear 315 are mounted to revolve 50 on a shaft 316 secured in a U-shaped frame 317, shown in Figs. 5, 7, 16 and 18, which is pivotally mounted on a shaft 318 secured in bearing blocks 319 carried by the casting 93. This frame 317 is suspended from the shaft 318, as shown in Figs. 16 and 18, and it has attached to 55 the lower end thereof a heavy leaf spring 320 which is adapted to be engaged at its lower end by a clamp 321, shown in Figs. 7, 13, 16 and 18, which is adapted to hold the bar 320 in the position shown by full lines in Fig. 16, in which position the gear 315 is held in mesh with the gear 143 and the guide wheel 57 is caused to engage the strap 40 with a resilient pressure at the place where this strap is in contact with the feed wheel 56. When the clamp 321 is released, the frame 317 and the bar 320 may swing upwardly to the position shown by dotted lines in 60 Fig. 16, which is of particular advantage when the strap is being threaded through the machine preliminary to the strapping operation. The clamp 321 comprises clamping lever 322 carrying a pin 323 adapted to engage the side of the lower end of the spring bar 320 and this pin 323 may be adjusted in order that the lower end of the bar will occupy the desired position and create the desired pressure of the guide wheel 57 on the strap passing over the feed wheel 56. The clamping lever 322 is pivoted at 324 on a bracket 325 carried by the frame member 86 and it is pivotally connected at 326 to a link 327

having a pivotal connection at an intermediate point 328 to another link 329 which is pivoted at 330 on the bracket 325. An operating lever 331 is pivoted at 332 on the lever 322 and is pivotally connected to the pin 328 which connects the links 327 and 329 so that a toggle connection is formed which permits the clamping lever 322 to be manipulated by the handle 331 to occupy the retracted position shown by full lines in Fig. 13 or the clamping position which is shown by dotted lines in that figure.

In order to prevent the operation of the mechanism when the strap is not being advanced properly by the feed wheel 56 due to interference or to buckling of the strap, means are provided for automatically opening the operating electric circuit when any such irregular condition exists. For this purpose, a shaft 335 is rotatably mounted in a bracket 336 carried by the casting 93, as shown in Figs. 6 and 7, and this shaft has mounted on one end thereof an arm 337 which is adapted to ride upon the surface of the strap 40 at or adjacent the feed wheel 56, while the other end of this shaft has mounted thereon a lever 338 having its free end connected by a pin 339 to a switch 340 which is connected in the electric operating circuit. A coil spring 341 is mounted on the shaft 335 with one end thereof bearing upon the arm 337 and with the other end thereof engaging the bracket 336 so that this spring tends to maintain the arm 337 in contact with the strap. If the strap buckles up due to interference in the gripping dogs or elsewhere, such buckling will occur in this region and the arm 333 is thereby elevated so that the lever 338 is caused to actuate the switch 340 to open the electric circuit and thereby stop the operation of the machine.

As previously described, after the strap has been gripped by the forward gripping dog 58 and the slack in the strap has been taken up by the reverse operation of the feed wheel 56, the strap is drawn taut around the package and a predetermined tension set up therein by the operation of the tensioning device 55 which is shown generally in Figs. 4a to 4f, inclusive. This tensioning device is better shown in Figs. 6, and 16 to 25, inclusive, where it is illustrated as comprising a gripping dog 345 pivoted at 346 on the end of a bar 347 which forms a part of a tilting frame adapted to be actuated as herein-after described in order to effect the tensioning of the strap. This bar 347 has mounted in the end thereof a gripping plate 348 having a serrated gripping surface which is adapted to coat with the teeth 345a of the gripping dog in gripping the strap which passes upwardly between the gripping dog 345 and the plate 348 from the source of supply which may be a reel carrying a coil of the strapping material. The gripping dog 345 has pivoted thereon by a bolt 349, a tripping member 350 which is adapted to control the operation of the gripping dog in cooperation with a stationary cam 351 which is secured by studs 352 to the casting 93. The tripping member 350 is provided with a transverse flange 350a adapted to engage the upright face of the dog 345 under the influence of a coil spring 353 which is secured to the upper corner of the member 350 and to a pin 354 carried by the bar 347 at a point to the left of the pivot 346 as viewed in Fig. 20. The tripping member 350 is further provided with a projecting finger 350b having a rounded end surface which is adapted to ride on the inclined surface 351a of the cam 351, and also to coat with a more sharply inclined cam surface 351b located at the lower end of this cam. The coil spring 353 acts normally to maintain the flange 350a in the upright position shown in Fig. 20 in contact with the gripping dog 345 and it also urges the gripping dog to a position where the finger 350b will engage the cam 351. At a point above the position occupied by the gripping dog 345 there is provided a stationary stop member 355 which is secured to the casting 93 to be engaged by the cam 345 at the proper time in the cycle of operations.

As shown in Fig. 20, the bar 347 is nearing the upper

end of its path of travel but the gripping dog 345 is still held out of engagement with the strap by the finger 350b of the tripping member which still rides upon the surface 351a of the cam. Upon further upward movement of the bar 347 to the position shown in Fig. 21, the finger 350b is extended to a point above the upper end of the cam surface 351a but the gripping dog 345 is still held out of engagement with the strap because the upper surface thereof then engages the stationary stop member 355. When the bar 347 of the tilting frame reaches to extreme upper position, as shown in Fig. 22, the top face of the gripping dog 345 is in contact with the complete lower end of the stop member 355 and the parts are then in readiness for the reverse movement of the member 347 which will bring about the tensioning of the strap about the package. As soon as this reverse movement of the member 347 begins, the gripping dog 345 passes away from the stop member 355 and is then moved by the spring 353 into engagement with the strap 40 while the finger 350b of the tripping member passes over the top shoulder 351d of the cam. Then, as the downward motion of the bar 347 continues, the gripping dog moves downwardly as shown by dotted lines in Fig. 23 with the spring 353 extended and with the finger 350b riding downwardly on the cam surface 351a.

At some point during the downward movement of the bar 347, which may be approximately that illustrated by dotted lines in Fig. 23, the strap 40 will have been drawn taut about the package, gripped by the rear gripping dog 62, and cut off by the shearing device 68. As soon as the strap 40 is cut off by the shearing device 68, the bar 347 being free of the restraint of the tensioned strap will quickly continue its downward movement until it occupies a position such as that shown in Fig. 24 where the finger 350b of the tripping member is adjacent the lower extremity of the cam surface 351b and the gripping dog 345 is still in engagement with the strap. As soon as the bar 347 begins its upward movement, the sharp incline of the surface 351b of the cam will engage the finger 350b and cause the gripping dog 345 to be tilted away from the strap so that the parts will then move upwardly with the finger 350b riding on the cam surface 351a and with the gripping dog out of engagement with the strap as shown in Fig. 25. These relative positions of the parts will then continue as the bar 347 moves back to the position shown in Fig. 20.

The bar 347 is formed as part of a tilting frame 360 which includes an upwardly extending Y-shaped frame structure 361 having the upper ends of its arms extending between the bar 347 and another bar 362. The members 347, 361 and 362 are secured together by bolts 363 and the members 347 and 362 are apertured for engagement by a sleeve 364 which is welded thereto and which is mounted to revolve upon a shaft 365 having its ends secured in bearings 366 which are carried by the previously described bracket 117 and by another bracket 367 which are welded to the top flanges of the channel-shaped frame members 90. Thus, the tilting frame 360 is mounted to rock upon the shaft 365 and this motion is effected by the previously mentioned cam 121 mounted upon the cam shaft 120, as shown particularly in Fig. 16. This cam is adapted to coat with a roller 370 which is mounted on a pin 371 extending between the bar 347 and the forward end of the bar 362. The cam 121 has a cam surface 121a of gradually increasing radius which is adapted to effect a gradual elevation of the tilting frame as the cam rotates in the direction of the arrow 372. At the end of this upward tilting movement of the frame 360 a gripping dog 345 grips the strap as heretofore described as the roller 370 begins a sharp travel toward the axis of the shaft 120 on the incline 121b of the cam.

The lower end of the stem portion of the Y-shaped frame structure 361 is pivotally connected at 374 to a link 375 which has a pivotal connection at 376 with the piston rod 377 which extends into the hydraulic cylinder

112 previously referred to where it is fixed to the piston 378. When fluid under pressure is admitted to the right-hand end of the cylinder 112, as viewed in Figs. 6 and 16, the piston rod 377 actuates the link 375 to move the tilting frame about the shaft 365 in a direction to cause the downward movement of the gripping dog 345 which is then in engagement with the strap and this fluid pressure is utilized to produce a predetermined tension in the strap before the strap is cut off and the joint is formed. The release of the tension in the strap by the cutting of the strap after a predetermined tension has been created releases the frame 360 so that the roller 370 is free to continue its inward travel on the cam surface 121b without resistance and, in order to prevent shock to the apparatus at the end of this tensioning stroke, the stem portion of the tilting frame 360 has secured thereto a rubber bumper 379 which is adapted to engage a stop plate 380 welded to the longitudinal frame members 81 and 87, as shown in Fig. 16. The overrunning clutch 138 (Fig. 9) prevents the shaft 135 from rotating in a direction opposite to that in which it rotates when driving the cam shaft, and overcomes the tendency induced by the roller 370 which tends to roll down the cam surface 121a when the cam 121 is in the rest position.

As previously indicated, the fluid pressure for operating the piston 378 is supplied from the accumulator 114 through the pipe 119. This accumulator 114 comprises a flexible sack (not shown) contained within an air-tight metal cylinder and the fluid under pressure is supplied to the interior of this sack from the pump 111 through the pipe 118. As the sack is filled with fluid, the air surrounding the sack within the metal container acts as a cushion to resist the inward flow of the fluid and to exert pressure tending to flow outwardly through the pipe 119 to the cylinder 112. The fluid pressure tending to actuate the piston 378 may be varied by operating the pump 111 through an operating handle 382, shown in Fig. 6, which may be reciprocated to pump additional fluid into the sack within the accumulator. The fluid pressure thus set up is applied continuously to the piston 378 and is released to cause the downward movement of the gripping dog 345 only when the roller 370 passes over the hump of the cam 121 and starts its movement inwardly on the cam surface 121b. After the tensioning operation has been completed the roller 370 then begins its travel outwardly on the gradually inclined surface 121a of the cam and the consequent motion of the tilting frame 360 takes place against the action of the compressed fluid in the cylinder 112. By regulating the fluid pressure acting upon the piston 378 the degree of tension set up in the strap when it is drawn taut around the package may be precisely controlled.

The strap 40 coming from the supply reel travels upwardly from the lower rear part of the machine through a guide channel 385 which is of the form shown in Fig. 17, comprising a bar 385a upon which is mounted a channel-shaped sheet metal cover 385b, thus forming an internal chamber through which the strap 40 passes as it is drawn upwardly by the feed wheel 56. The upper end of the guide member 385 is attached to the lower part of the plate 386 which is attached to the forward end of the bar 347 and extends downwardly therefrom. The lower end of the guide channel 385 carries a plate 387 which is provided with a transverse slot 387a engaged by an adjusting screw 388 mounted in the lower part of the tilting frame 360. The extreme lower end of the guide channel 385 carries a channel-shaped bracket 389 in which there is rotatably mounted a roller 390 beneath which the strap 40 extends as it passes from the supply reel (not shown) to the lower end of the guide channel.

After emerging from the upper end of the guide channel 385, the strap 40 passes around a series of curling rolls 391, 54, 393 and 394 which are mounted on the plate 386 and which causes the strap to follow an irregu-

lar path adapted to impart thereto a longitudinal bow or curvature so that when the strap emerges from the guide member 37, as shown in Fig. 1, it will have a curvature such that it may be readily passed around the package and moved into engagement with the guide channel 61b. The shaft 395 upon which the roller 54 is mounted is adapted to be clamped in adjusted position in radial slots 386a which are formed in the plate 386 so that its position may be regulated to determine the degree of curvature imparted to the strap which passes over the top of the roller 391, then around the roller 54, and then between the rollers 393 and 394.

In order that the roller 393 may be moved from its operating position to facilitate the threading of a strap 15 through the rolls and upwardly between the gripping dog 345 and the gripping plate 348, the roller 393 is mounted on a shaft 396 between the ears 397a which are formed on the upper end of a block 397. This block is pivoted at 399 on the lower ends of the plate 386. The shaft 396 has an enlarged portion 396a which is adapted to extend over a shoulder 386b formed on the plate 386, and this enlarged portion of the shaft is hollowed out on one side to form a cavity in which a latch member 398 is pivoted at the point 399. A spring 400 is secured to the top of this latch member and bears against the wall of the cavity to force the latch member normally into engagement with the notch 386c formed on the shoulder 386b of the plate 386. By pressing up on the latch member, the block 397 may be swung forwardly to move the roller 393 out of its normal operative position.

Instead of actuating the tilting frame 360 by the fluid pressure operated mechanism shown in Figs. 6, 7 and 16 to 19, inclusive, it may be desirable in some instances, for purposes of economy, to use the modified actuating mechanism which is shown particularly in Figs. 26 and 27. 35 In this modified construction the tilting frame 360 is constructed and mounted as previously described and the roller 370 is actuated by the cam 121, the only difference being that the stress set up by the torsional twisting of a shaft is utilized for tilting the frame 360 in response to the rotation of the cam. For this purpose, the bars 347 and 362 are connected by a sleeve 405 which extends through apertures in both members and is journaled in a bearing member 406 carried by the bracket 417 previously referred to. This sleeve has mounted within it a shaft 407 and both the sleeve and the shaft extend to the opposite side of the machine where they are welded together and journaled in a suitable bearing, not shown. Except at this far side of the machine where 50 the sleeve and the shaft are welded together, they have no connection with each other and the shaft is free to twist within the sleeve. At the other side of the machine the shaft 407 extends beyond the sleeve 405 and is journaled in a bearing member 408 secured to the frame structure. The shaft extends through this bearing and has rigidly secured thereto an arm 410 which extends toward the forward side of the machine and is pivotally connected at its end to a block 411 by means of a bolt 412. This block has an aperture which is internally 55 threaded for engagement by an adjusting screw 414 which is provided at its upper end with an operating wheel 415. The lower end of this adjusting screw engages a socket member 416 which is pivoted at 417 to an ear 418 carried by the frame structure. The adjusting screw 414 has an enlarged head 414a which is adapted to coact with the top flange 416a of the socket member to prevent relative endwise movement of these parts when the adjusting screw is rotated. By turning the wheel 415 the adjusting screw will move the block 411 longitudinally 60 of the adjusting screw, thereby twisting the torsion shaft 407 and the sleeve 405 which is transmitted through the tilting frame to cause the frame to tilt in a forward direction when it is permitted to do so by the rotation of the cam 121. In order that the sleeve 405 and the shaft 407 65 will twist to the same degree, the cross-sectional areas 70 75

of these two members should be matched to the extent that their movements of inertia are substantially identical. Thus, when the roller 370 passes over the hump of the cam 121 the roller immediately passes downwardly over the surface 121b of the cam to cause a downward movement of the arm 347 and a corresponding tensioning movement of the gripping dog 345. Although this structure is provided with the bumper 379 and the stop plate 380 as in the construction first described, there is also an additional means for relieving the shock at the end of the tensioning movement when the strap is cut. For this purpose, there is provided a shock absorber 420 of the rotary type which is secured to the lower part of the frame structure and which has an operating crank 421 connected by a link 422 which is pivoted at 423 on the tilting frame 360. This link 422 is preferably formed in two parts which have threaded engagement with an intermediate sleeve 422a so that the effective length of this member may be varied as desired. The arrangement shown in Figs. 26 and 27 provides a simple form of construction which may be satisfactorily used in many instances in place of the fluid pressure operated mechanism previously described but it has the disadvantage that it does not have a wide range of operation and it may therefore be necessary, at times, to substitute other sleeves and torsional shafts of different dimensions for the sleeve 405 and the shaft 407.

Before proceeding with a description of the electric system by which various parts of the machine are controlled and operated, reference will be made to the physical construction of some of the parts which are included in the electric system. As shown particularly in Figs. 5 and 6, the lower front horizontal frame member 80 has welded thereto two depending arms 425 between which there is pivotally mounted on a shaft 426 the foot pedal 46 previously referred to. This foot pedal is of substantial length and is of L-shaped cross section so that it may be readily engaged by the foot of the operator in any desired position within a considerable range. Attached to the foot pedal is an upstanding arm 427 which is adapted to operate the plunger 428 of an electric switch 429 which is included in the electric circuit and which is adapted to control the operation of the feeding mechanism so that the operator may readily cause any desired length of strap to be projected outwardly over the strapping table as shown in Fig. 1.

As shown in Figs. 5 and 7, the cam shaft 120 has its right-hand end connected by a universal joint 429 with a shaft 430, which extends to another universal joint 431 by which it is connected to an auxiliary cam shaft 432. The shaft 430 is preferably formed in two parts having a telescoping interlocking engagement with each other in a sleeve 430a. The auxiliary cam shaft has secured thereon within a housing 433 a series of cams 434, 435, 436, 437, and 438 which are arranged to actuate certain switches included in the electric circuit as hereinafter described.

The electric system by which the operation of the machine is controlled is illustrated somewhat diagrammatically in Fig. 28 where the electric current, such as 110 volt, 60 cycle, alternating current, is furnished by supply conductors 444 leading through the master switch 445 to the line conductors 446 and 447 between which various branch circuits are connected. The line conductor 447 leads to a control switch 450 which has four pairs of contacts 450a, 450b, 450c, and 450d. The contacts of each pair are adapted to be connected with each other by one or the other of the connecting bars 450e and 450f which are carried by the operating plunger 450g of the switch. When the plunger 450g is in its lower position as shown in Fig. 28, the contacts 450b are connected and a circuit is thereby completed from the line conductor 446 through the conductor 448, electric motor 85, and conductor 449, to the contacts 450b so that the motor is thereby caused to operate. When the plunger 450g is down, the con-

tacts 450d are closed by the member 450f and a connection is thereby established through the conductors 451a, 451, and the pilot light 452 to the other line conductor 446 so that the pilot light then remains in operation. An auxiliary line conductor 453 is connected to the branch line 454 and has connected thereto various branch lines extending from the line conductor 446. A conductor 443 connects the conductor 453 with the conductor 451.

A conductor 463 extends from the conductor 453 to the line conductor 446 through a relay 456 which controls the drive of the cam shaft 120. Another branch conductor 464 leads from the line conductor 446 through a relay 457 adapted to control the strap feed and through a switch 457a to the conductor 453. A switch 435a operated by the cam 435 is connected in the line 453 between the conductors 463 and 464. A conductor 465 extends from the line conductor 446 through a relay 458, a switch 434a operated by the cam 434, and a switch 458b to the conductor 453. The relay 458 is adapted to operate in conjunction with the switch 434a to control the resetting of the cycle.

At a point between the switches 434a and 458b the conductor 465 is connected by a conductor 466 to one terminal 45a of the cycle switch 45 which is mounted beneath the panel 41 at the front of the machine. The other terminal 45b of this switch is connected by a conductor 467 through a switch 458a, controlled by the relay 458, to the previously mentioned conductor 463. The switch arm 45c of the switch 45 is connected by a conductor 468 to one terminal 429a of the foot pedal switch 429 and the movable contact 429b of this switch is connected by a conductor 469 to the conductor 453. The lower stationary terminal 429c of the foot pedal switch is connected by a conductor 470 to one end of a conductor 471 which leads through a relay 461 to the line conductor 446, the relay 461 being adapted to control the feeding of the strap.

The conductor 468 which connects the cycle switch 45 with the foot pedal switch 429 is connected by a conductor 473 to one terminal of a switch 436a which is operated by the cam 436 and the other terminal of this switch is connected to a conductor 474 which establishes a connection through a strap take-up relay 459 to the line conductor 446, thereby providing means for controlling the taking up of slack by the reverse operation of the feed wheel. A conductor 475 is connected to the conductor 474 between the switch 436a and the relay 459 and this conductor leads to one terminal of each of two switches 455a and 460a which are connected in parallel with each other and in series with a relay 460 which is connected between the switches 455a and 460a and the line conductor 446 by means of a conductor 476. The relay 460 is adapted to cooperate with the connected switches in controlling the operation of the rotary switch 106.

The rotary switch is further controlled by the previously mentioned relay 455 and by the switch 460b which is operated by the relay 460. A conductor 480 is connected to the branch line 454 between the relay 455 and the switch 460b and extends to one terminal 106b of the rotary switch 106. This switch has a movable contact arm 106c which is connected by conductors 481 and 482 to the conductor 453. The other stationary terminal 106a of the rotary switch is connected by a conductor 483 to one of the pair of contacts 485a of an electronic timer 485. The other contact of this pair is connected by a conductor 486 to the conductor 464 between the relay 457 and the switch 457a which is operated thereby. The timer 485 has a lower pair of contacts 485b, one of which is connected by a conductor 487 through a switch 457b, operated by the relay 457, to the conductor 481, while the other contact is connected by a conductor 492 and the conductor 470 to the foot pedal switch 429. One or the other of the two pairs of contacts 485a and 485b are adapted to be connected with each other by a

plunger 488 operated by a solenoid 489 which is connected in the circuit in the usual manner. The timer also comprises a terminal 485c which is connected by a conductor 490 to the conductor 482 and a terminal 485d which is connected by a conductor 491 to the supply line 446. The electronic timer also includes a vacuum triode tube 485e, the grid of which has connected in series therewith a condenser 493 and a potentiometer 494. Other terminals 495 of this electronic timer are connected by conductors 496 to a switch 438a which is operated by the cam 438.

The conductors 446 and 453 are also connected to the primary terminals of a rectifier 500 which supplies direct current at a moderate voltage, such as 90 volts, to an auxiliary circuit which includes the windings of the feed drive clutch 160, the feed drive brake 170, the cam drive clutch 180, the cam drive brake 195, and the take-up drive clutch 205. The connection to one terminal of each of these windings is made through a conductor 501 which is also connected to each of the condensers which are included in parallel with these windings. The connection to the other terminals of the windings of these clutches and brakes is made from the other direct current terminal of the rectifier 500 by a conductor 502 which has connected therein the strap jamming switch 340 which is adapted to operate to interrupt the circuit when there is any substantial interference with the movement of the strap over the feed wheel 56. The conductor 502 is connected by a conductor 503 to one terminal of a switch 456a which is operated by the previously described relay 456 and the other terminal of this switch is connected by a conductor 504 to the other terminal of the winding of the cam drive clutch 180. Another conductor 505 leads from the conductor 502 to one terminal of a switch 456b which is operated by the relay 456 and which has its other terminal connected by a conductor 506 to the other terminal of the cam drive brake 195.

The other clutches and the take-up brake are operated through a circuit comprising the branch conductor 508 which is connected to the conductor 502 and which is connected by a conductor 509 to one terminal of a switch 461b, operated by the relay 461, which has its other terminal connected through a conductor 510 and a resistor 511 to the other terminal of the winding of the feed drive clutch 160. The conductor 508 is also connected by a conductor 512 with the contacts of a switch 461a, operated by the relay 461, which are adapted to be closed by the common contact member 513 which is also actuated by the solenoid 461 to close the contacts 461b. A conductor 514 leads from the switch contacts 461a to one terminal of a switch 459b which is operated by the relay 459 and which is connected through a conductor 515 and a resistor 516 to the other terminal of the feed and take-up brake 170. A conductor 517 leads from the conductor 502 to one terminal of a switch 459a which is operated by the relay 459 and which has its other terminal connected through a conductor 518 and a rheostat 519 to the other terminal of the take-up drive clutch 205. The switches 459a and 459b have a common movable contact member 520 so that both switches cannot be closed simultaneously.

A conductor 525 leading from the line conductor 446 is connected to one terminal of a winding 526a forming a part of a pneumatic timer 526. Another conductor 527 leading from the conductor 449 is connected to the other terminal of the winding 526a through a welding switch 528 and a switch 537a which is operated by the cam 537. A conductor 529 leads from the conductor 525 to one terminal of the winding 530a of a welding contactor 530 and the other terminal of that winding is connected to the conductor 527 through a conductor 531 which has connected therein a pneumatic timer switch 532. The welding contactor has a movable core 530b, operated by the solenoid winding 530a, to close a pair of contacts 533 which are connected in one of two conductors 534 leading from a

220 volt, 60 cycle supply line 535 and connected to the primary winding 100a of the transformer 100 previously referred to. The secondary winding 100b of this transformer is connected by the conductors 536 to the welding contacts 295 and 296.

- Assuming that all parts of the machine are at rest and in the starting position shown in Fig. 4a with a package 50 in place on the table 32 in readiness to be bound, the operator grasps the end 40a of the strap and holds it 10 around the package until the free end is threaded through the groove 32a in the table into engagement with the guide channel 61b of the guide 61. The operator then closes the master switch 445 and also actuates the control switch 450 to move its plunger to the lower position 15 wherein the contacts 450b and 450d are closed. As a result of these operations the motor 85 starts rotating and the rectifier 340 is energized to supply direct current to the circuit of the magnetic clutches and brakes 160, 170, 180, 195 and 205. The solenoid 456 of the cam drive relay is then deenergized so that its contacts 456a are open and its contacts 456b are closed, thus maintaining the cam drive clutch 180 deenergized while energizing the cam drive brake 195. At this time, the solenoid 459 of the strap take-up relay is also deenergized so that 20 its contacts 459a are open and its contacts 459b are closed, thus maintaining the take-up drive clutch 205 deenergized while at the same time energizing the take-up brake 170. Also, the solenoid 461 of the strap feed relay is deenergized so that its contacts 461a are closed and its contacts 461b are open, thus keeping the feed and take-up brake 170 energized while holding the feed drive clutch 160 deenergized. At this time the solenoid 458 of the cycle reset and non-repeat relay is energized through the foot pedal switch 429, the cycle switch 45, and the cycle 25 reset switch 434a, whereby the contacts 458a are closed to permit the solenoid 456 of the cam drive relay to become energized when the cycle switch 45 is later actuated to close the contact 45b, and the contacts 458b are closed thus establishing a holding circuit which keeps the 30 solenoid 458 energized when the cycle switch 45 is actuated to engage the contact 45b. The closing of the switches 445 and 450 also energizes the solenoid 455 of the rotary switch relay through the contacts 106b of the rotary switch 106. This opens the contacts 455a which 35 prevents the solenoid 460 of the rotary switch holding relay from being energized when the switch 436a is closed. Finally, the closing of the switches 445 and 450 energizes the circuit of the electronic timer 485 so that it starts to warm up.
- Assuming that the end of the strap has been inserted in the guide channel 61b as previously mentioned, the operator then presses the cycle switch 45 which breaks the contact 45a and closes the contact 45b, thereby energizing the solenoid 456 of the cam drive relay through the contacts 458a of the cycle reset and non-repeat relay. This 40 opens the contacts 456b to deenergize the cam drive brake 195 and it also closes the contacts 456a to energize the cam drive clutch 180 so that the cam shaft 120 then starts rotating.
- After the cam shaft has rotated through an angle of about 6 degrees, the switch 435a closes to keep the solenoid 456 of the cam drive relay energized after the cycle switch contact 45b is opened when the switch 45 is released by the operator. It is necessary to hold the switch 45 closed only long enough to establish this holding circuit.
- After the cam shaft 120 has rotated through an angle of about 10 degrees from its starting position, the switch 434a is opened by the cam 434 with the result that the 45 solenoid 458 of the cycle reset and non-repeat relay is deenergized. The contacts 458a are then opened with the result that the solenoid 456 of the cam drive relay cannot be energized through the cycle switch 45 but it is maintained energized through the switch 435a. The contacts 458b are also then opened with the result that the 50
- 70

solenoid 458 cannot again be energized until the switch 434a has been closed by the cam 434 after the cam shaft has rotated through an angle of about 293 degrees. With the contacts 458b opened the machine is prevented from repeating a cycle even if the cycle switch 445 is unintentionally pressed too long by the operator.

After the cam shaft has rotated through an angle of about 8 degrees the switch 438a is opened and this serves to prepare the electronic timer 485 so that it will time the duration of the strap feed when this switch is subsequently closed. When the triode vacuum tube 485e of the electronic timer is warmed up, the solenoid 489 in its plate circuit is normally energized because the current is then flowing through the vacuum tube 485e. With the solenoid 489 energized, the relay contacts 485a are closed and the relay contacts 485b are open. Normally, when the switch 438a is open, the timing condenser 493 maintains a full charge. As soon as the switch 438a is closed, the timing condenser 493 places a high negative potential upon the grid of the triode vacuum tube 485e and thereby stops the flow of current therethrough. The solenoid 489 in the plate circuit of the tube 485e is then deenergized with the result that the relay contacts 485a open and the relay contacts 485b close. The timing condenser 493 then discharges through the potentiometer 494 and when the negative potential on the grid of the triode vacuum tube 485e is reduced sufficiently due to this discharge, the tube 485 again conducts current and the solenoid 489 of the relay is reenergized so that the contacts 485a again close and the contacts 485b again open. The discharge time of the condenser 493 determines the period during which the vacuum tube 485 does not conduct current and the time period during which the solenoid 489 of the relay is deenergized, thereby determining also the time period during which the contacts 485b are closed. Since the contacts 485b are in series with the solenoid 461 of the strap feed relay, this time period so determined is the period during which the strap is fed by the feed wheel 56. This time period may be varied by adjusting the potentiometer 494 to regulate the discharge time of the condenser 493. When the switch 438a is opened at the end of the timing period, it merely permits the condenser 493 to be recharged in preparation for another cycle.

After the cam shaft has rotated through an angle of about 22 degrees the switch 435a is opened by the cam 435 and this deenergizes the solenoid 456 of the cam drive relay with the result that the contacts 456a are opened to deenergize the cam drive clutch 180 and the contacts 456b are closed to energize the cam drive brake 195. Because of the normal delay in the operation of the switches and of the clutch 180 and the brake 195, the cam shaft 120 actually does not come to rest until after it has rotated through about 36 degrees even though the switch 435a is actuated after a rotation of about 22 degrees.

After the cam shaft has rotated through about 27 degrees the switch 436a is closed by the cam 436 and this energizes the solenoid 459 of the strap take-up relay so that the contacts 459b are opened to deenergize the feed and take-up brake 170. Also, the energization of the solenoid 459 closes the contacts 459a to energize the take-up drive clutch 205 and thereby start the reverse operation of the feed wheel 56 which takes up the slack in the strap extending around the package. As the strap take-up starts, the contact 106b of the rotary switch 106 opens and the contact 106a is closed, thereby energizing the solenoid 457 of the strap feed prevention relay, assuming that the triode vacuum tube 485e has been warmed up and is therefore conducting current. When the solenoid 457 is energized it closes the contacts 457a and 457b which establishes holding circuits to maintain the solenoid 457 energized until the machine has been shut down by the opening of the master switch 445. The closing of the contacts 457b completes the circuit through the

solenoid 461 of the strap feed relay so that when the contacts 485b are later closed through the operation of the switch 438a, the solenoid 461 can be energized. The purpose of the solenoid 457 is to prevent the strap from feeding in case the electronic timer 485 has not been warmed up.

The opening of the contact 106b deenergizes the solenoid 455 of the rotary switch relay and this closes the contacts 455a, thereby energizing the solenoid 460 which closes the contacts 460a and 460b. The closing of the contacts 460b permits the solenoid 456 of the cam drive relay to be energized when the rotary switch 106 is actuated to close the contact 106b immediately upon the stoppage of the take-up drive shaft. The rotary switch 106 is in position with its contacts 106a closed while the take-up drive shaft is rotating to cause the feed wheel to take up the slack in the strap around the package. When this slack has been removed, the feed wheel 56 and its complementary wheel 57 stall and the take-up drive shaft stops rotating, whereupon the contacts 106b close and the contacts 106a open, the switch being one which causes its contacts to occupy one position when the shaft is rotating and the other position when the shaft is at rest. When the contacts 106a are thus closed, the solenoid 456 is energized to cause the cam shaft to resume its rotation. When the solenoid 456 is energized, the cam drive clutch 180 is energized through the contacts 456a and the cam drive brake 195 is deenergized by the opening of the contacts 456b. The closing of the contacts 460a maintains the solenoid 460 of the rotary switch holding relay energized when the contacts 455a are later opened.

After the cam shaft has rotated through about 48 degrees the switch 435a is closed by the cam 435 and this holds the solenoid 456 of the cam drive relay energized even after the subsequent opening of the switch 436a by the rotation of the cam 436. This opening of the switch 436a takes place after the cam shaft has rotated through about 108 degrees with the result that the solenoid 460 is deenergized and the contacts 460a and 460b are opened. The opening of the contacts 460a insures that the solenoid 460 will not again be energized until the switch 436a closes during the next cycle and the opening of the contacts 460b permits the switch 435a, which is now closed, to keep the solenoid 456 of the cam drive relay energized. Upon the opening of the switch 436a, the solenoid 459 of the strap take-up relay is deenergized with the result that the contacts 459a are opened to deenergize the take-up drive clutch 205 and the contacts 459b are closed to energize the brake 170.

After the cam shaft has rotated through about 218 degrees, the switch 537a is closed by its cam 537 with the result that the relay solenoid 526a in the pneumatic timer 526 is closed to start the timing of the welding operation. At the same time, the solenoid 530a of the welding contactor energizes to close the switch 533 and thereby energize the welding transformer 100. At the expiration of the time interval for which the pneumatic timer 526 is set, it automatically opens the switch 532 to deenergize the solenoid 530a and thereby open the switch 533 to deenergize the welding transformer 100 and thereby terminate the welding operation. After the cam shaft has rotated through about 280 degrees the switch 537a is opened by its cam and this deenergizes the relay solenoid 526a in the pneumatic timer to reset it for timing the welding during the next succeeding cycle of the machine.

When the cam shaft 120 has rotated through about 345 degrees the switch 435a is opened by its cam 435 and this deenergizes the solenoid 456 thereby opening the contacts 456a to deenergize the cam drive clutch 180 while at the same time closing the contacts 456b to energize the cam drive brake 195.

When the cam shaft 120 has rotated through 350 degrees, the switch 438a closes in response to the rotation

of its cam and this causes the timing condenser 493 to place a high negative potential upon the grid of the triode vacuum tube 485 and thereby stop the flow of current therethrough as previously described. This stoppage de-energizes the solenoid 489 to open the contacts 485a and to close the contacts 485b. This action energizes the solenoid 461 of the strap feed relay, thereby opening the contacts 461a and closing the contacts 461b. The feed and take-up brake 170 is thereby deenergized and the feed drive clutch 160 is energized to start the feeding of the strap to project a portion of strap into the position shown in Fig. 1 near the end of the cycle. When the timing condenser 493 has discharged sufficiently, the tube 485 again begins to conduct electric current and the solenoid 489 is again energized to close the contacts 485a and to open the contacts 485b. This results in de-energizing the solenoid 461 of the strap feed relay which closes the contacts 461a and opens the contacts 461b. The feed drive clutch 160 is thereby deenergized to permit the stoppage of the strap feeding operation and the take-up brake 170 is energized to effect a positive stoppage of the rotation of the feed shaft. After it has rotated through a full revolution, the cam shaft 120 coasts to a stop and the machine is ready to start upon a new cycle of operations which is initiated by again closing the cycle switch 45.

The control switch 450 normally occupies the lower position shown in Fig. 28 when the machine is in automatic operation as heretofore described, but the plunger 450g of the switch may be elevated to close the contacts 450a and 450c which is desirable as a precautionary measure when the operator has not inserted the strap to the full extent into the strap end guide 51. In such a case, when the operator presses the cycle switch 45 to start the rotation of the cam 120, the forward gripping dog 58 is moved upwardly without gripping the strap against the stationary plate 60 but the cam shaft will continue to rotate as usual through 36 degrees when it stops as heretofore described. The feed drive clutch 160 then drives the feed wheel 56 in a reverse direction to remove the slack in the strap around the package but, since the leading end of the strap is not gripped by the gripping dog 58, this reverse operation pulls the strap off of the package and back to a point where its end passes through the wheels 56 and 57. Since there is no resistance to this rotation of the feed wheel 56 it will continue rotating and will not cause the rotary switch 106 to alternate the position of its contacts and thereby actuate the cam drive clutch 180 to start the cam shaft rotating. When this condition arises the control switch 450 is promptly turned to the upper or manual position which deenergizes the motor and energizes the cam drive relay 456 so that the clutch 180 is energized to connect the cam shaft 120 with the motor. Then, even though the motor is deenergized, it coasts to a stop and it has been found that its inertia is sufficient to drive the cam shaft 120 past the 48 degree position at which time the switch 435a is closed. When this switch is closed the control switch 450 can again be turned to its lower automatic position and the motor again energized to carry the machine through the remainder of its operating cycle.

As a precaution, the welding switch 528 may be opened before operating the control switch 450 to restore it to the automatic position in order to prevent a welding operation when there is no strap in position to be welded. After this faulty cycle of operations has been completed, the strap may again be rethreaded through the machine and a new cycle can then be performed in the usual manner.

Although one form of the improved box strapping machine, with a modification of a portion thereof, has been illustrated and described by way of example in connection with the explanation of a preferred mode of operation, it will be understood that the invention may be con-

structed in various ways without departing from the scope of the appended claims.

We claim:

1. The combination in a box strapping machine, of means for supporting a box in strapping position, means for loosely supporting adjacent said position the end of a strap leading from a supply, means for gripping said strap end after the strap has been manually withdrawn and extended around a box in said position, means for taking up the slack in the strap around said box, independent means for drawing the strap taut around the box, means independent of said previously named means for gripping the supply portion of the strap and holding the same in a position overlapping said end, means for cutting off the supply portion, and means independent of either of said gripping means for then uniting the overlapping ends of the strap.
2. The combination in a box strapping machine, of means for supporting a box in strapping position, means for supporting the end of a strap leading from a supply, means for holding said strap end after the strap has been manually withdrawn and extended around a box in said position, means for taking up the slack in the strap around said box, independent means for drawing the strap taut around the box, means for holding the supply portion of the strap overlapping said end, means for cutting off the supply portion, means for then uniting the overlapping ends of the strap, and means for then ejecting the strap from said holding means.
3. The combination in a box strapping machine, of means for supporting a box in strapping position, feeding means for withdrawing strap from a supply and moving the end thereof to said position, means for holding the end of the strap after it has been manually further withdrawn and extended entirely around a box in said position, means for reversing said feeding means to tighten said strap around said box, additional means independent of said feeding means for then drawing the strap taut around the box, means for holding the supply portion of the strap adjacent to but independently of said end, means for then cutting said supply portion to form a second strap end overlapping said first named end, and means for forming a joint between said ends.
4. The combination in a box strapping machine, of means for supporting a box in strapping position, feeding means for withdrawing strap from a supply and moving the end thereof to said position, stop means engaging the end of said strap for locating and orienting the end of said strap in a predetermined place when it is further withdrawn and extended entirely around a box in said position, means for then holding said end, means for tightening the strap around said box, means for cutting the supply portion of said strap to form a second end, and means for joining said ends.
5. The combination in a box strapping machine, of means for supporting a box in strapping position, feeding means for withdrawing strap from a supply and moving the end thereof to said position, stop means engaging the end of said strap for locating and orienting the end of said strap in a predetermined place when it is further withdrawn and extended entirely around a box in said position, means for then holding said end, means for reversing said feeding means to take up the slack in the strap around said box, and means for holding the supply portion of the strap adjacent said end.
6. The combination in a box strapping machine, of means for supporting a box in strapping position, feeding means for withdrawing strap from a supply and moving the end thereof to said position, stop means engaging the end of said strap for locating and orienting the end of said strap in a predetermined place when it is further withdrawn and extended entirely around a box in said position, means for then holding said end, means for reversing said feeding means to take up the slack in the strap around said box, and additional means for gripping said strap and

pulling it to set up a predetermined tension in the strap extending around said box.

7. The combination in a box strapping machine, of means for supporting a box in strapping position, feeding means for withdrawing strap from a supply and moving the end thereof to said position, stop means engaging the end of said strap for locating and orienting the end of said strap in a predetermined place when it is further withdrawn and extended entirely around a box in said position, means for then holding said end, means for reversing said feeding means to take up the slack in the strap around said box, additional means for gripping said strap and pulling it to set up a predetermined tension in the strap extending around said box, means for then holding the supply portion of the strap adjacent said end, means for cutting said supply portion to form a second strap end overlapping said first named strap end, and means for uniting said ends.

8. The combination in a box strapping machine, of a table for supporting a box in strapping position, said table having a groove beneath said position, means for withdrawing strap from a supply and feeding it to said position, a guide beneath said box for receiving and positioning the end of said strap when it is further withdrawn from said supply and inserted through said groove, means for gripping the end portion of the strap adjacent said guide, means for drawing the strap taut, means for gripping the supply portion of said strap, and means for moving said guide laterally out of engagement with said strap.

9. The combination in a box strapping machine, of a table for supporting a box in strapping position, said table having a groove beneath said position, means for withdrawing strap from a supply and feeding it to said position, a guide beneath said box for receiving and positioning the end of said strap when it is further withdrawn from said supply and inserted through said groove, means for gripping the end portion of the strap adjacent said guide, means for then tightening the strap around the box, means for then gripping the strap adjacent said strap end, means for then cutting off the strap from the supply to form a second strap end overlapping said first named strap end, and means for moving said guide laterally out of engagement with said strap.

10. The combination in a box strapping machine, of a table for supporting a box in strapping position, said table having a groove beneath said position, means for withdrawing strap from a supply and feeding it to said position, a guide beneath said box for receiving and positioning the end of said strap when it is further withdrawn from said supply and inserted through said groove, means for gripping the end portion of the strap adjacent said guide, means for then tightening the strap around the box, means independent of said first gripping means for then gripping the strap adjacent said strap end, means for then cutting off the strap from the supply to form a second strap end overlapping said first named strap end, means for welding said strap ends together, and means for automatically causing all of said operations except said strap withdrawal to take place sequentially in proper timed relation.

11. The combination in a box strapping machine, of a table for supporting a box in strapping position, said table having a groove beneath said position, feeding means for withdrawing strap from a supply and moving it endwise beneath said position to said table, a guide for directing the end of the moving strap over said position, means beneath said position for gripping the end of the strap looped over a box in said position and inserted in said groove, and means for imparting a longitudinal curvature to said strap before it reaches said guide and said position to cause the strap to extend over a box in said position.

12. The combination in a box strapping machine, of means for supporting a box in a position to be strapped, means for withdrawing strap from a supply and feeding

it to said position, means under said position for guiding said strap and for receiving the end of the strap after it has been extended around a box, gripping means for holding said end of said strap after it has engaged said guiding means, means for tensioning the strap around the box, a second gripping means for then holding the supply portion of the strap, means for retracting the guiding means from the vicinity of said end of said strap, means for cutting the strap from the supply to form a second end overlapping said first named end, and means for welding said overlapping ends together.

13. The combination in a box strapping machine, of means for supporting a box in a position to be strapped, means for withdrawing strap from a supply and feeding it to said position, means under said position for guiding said strap and for receiving the end of the strap after it has been extended around a box, gripping means for holding said end of said strap after it has engaged said guiding means, means for tensioning the strap around the box, a second gripping means for then holding the supply portion of the strap, means for retracting the guiding means, means for cutting the strap from the supply to form a second end overlapping said first named end, means for welding said overlapping ends together, and means including a cam shaft having a series of cams mounted thereon for operating some of said means.

14. The combination in a box strapping machine, of means for supporting a box in a position to be strapped, means for withdrawing strap from a supply and feeding it to said position, means under said position for guiding said strap and for receiving the end of the strap after it has been extended around a box, gripping means for holding said end of said strap after it has engaged said guiding means, means for tensioning the strap around the box, a second gripping means for then holding the supply portion of the strap, means for retracting the guiding means, means for cutting the strap from the supply to form a second end overlapping said first named end, means for welding said overlapping ends together, and means including a cam shaft having a series of cams mounted thereon for operating some of said means.

15. The combination in a box strapping machine, of means for supporting a box in a position to be strapped, means for withdrawing strap from a supply and feeding it to said position, means under said position for guiding said strap and for receiving the end of the strap after it has been extended around a box, gripping means for holding said end of said strap after it has engaged said guiding means, means for tensioning the strap around the box, a second gripping means for then holding the supply portion of the strap, means for retracting the guiding means, means for cutting the strap from the supply to form a second end overlapping said first named end, a pair of welding contacts positioned above said strap ends and connected in a welding circuit, a welding head movable between said gripping means to press said strap ends against said contacts, and means for actuating said welding head.

16. The combination in a box strapping machine, of

means for supporting a box in a position to be strapped, means for withdrawing strap from a supply and feeding it to said position, means under said position for guiding said strap and for receiving the end of the strap after it has been extended around a box, gripping means for holding said end of said strap after it has engaged said guiding means, means for tensioning the strap around the box, a second gripping means for then holding the supply portion of the strap, means for retracting the guiding means, a strap shearing device, means for advancing said device to embrace the supply portion of the strap and then actuating it to shear said strap to form a second strap end overlapping said first named strap end, and means for welding said ends together.

17. The combination in a box strapping machine, of means including a feed wheel for feeding a strap to a box strapping position, a feed shaft on which said wheel is rotatably mounted, a countershaft connected to drive said feed wheel, power actuated means, a magnetic clutch for connecting said power actuated means to said countershaft to drive said feed wheel in one direction, a magnetic brake for stopping the rotation of said countershaft, and an operating electric circuit having means for insuring that said clutch and said brake are not operated simultaneously.

18. The combination in a box strapping machine, of means including a feed wheel for feeding a strap to a box strapping position, a feed shaft on which said wheel is rotatably mounted, a countershaft connected to drive said feed wheel, power actuated means, a magnetic clutch for connecting said power actuated means to said countershaft to drive said feed wheel in one direction, and a magnetic clutch for connecting said power actuated means to said feed wheel to rotate said feed wheel in the opposite direction.

19. The combination in a box strapping machine, of means including a feed wheel for feeding a strap to a box strapping position, means for gripping the end of a strap extended around a box in said position, a feed shaft on which said feed wheel is rotatably mounted, a countershaft connected to drive said feed wheel, a cam shaft driven by said feed shaft, means including a cam fixed on said cam shaft for controlling the operation of said gripping means, power actuated means, means for connecting said power actuated means to said countershaft to drive said feed wheel, and means for connecting said power actuated means to said feed shaft to actuate said cam shaft.

20. The combination in a box strapping machine, of means including a feed wheel for feeding a strap to a box strapping position, means for gripping the end of a strap extended around a box in said position, a feed shaft on which said feed wheel is rotatably mounted, a countershaft connected to drive said feed wheel, a cam shaft driven by said feed shaft, means including a cam fixed on said cam shaft for controlling the operation of said gripping means, power actuated means, means for connecting said power actuated means to said countershaft to drive said feed wheel, means for connecting said power actuated means to said feed shaft to actuate said cam shaft, means for stopping the rotation of said countershaft, and means for connecting said power actuated means directly to said feed wheel to rotate said feed wheel in a direction opposite to that in which it is rotated by said countershaft.

21. The combination in a box strapping machine, of means for supporting a box in strapping position, means including a feed wheel for feeding a strap to said position, means for gripping the end of a strap extended around a box in said position, a feed shaft on which said feed wheel is rotatably mounted, a countershaft connected to drive said feed wheel, a tensioning device for drawing said strap taut around the box after it is held by said gripping means, a cam shaft connected to be driven by said feed shaft, means including cams fixed on said cam shaft for controlling the operation of said gripping means and said tensioning device, power actuated means, means for connecting said power actuated means to said countershaft to drive said feed wheel, and means for connecting said power actuated means to said feed shaft to actuate said cam shaft.

22. The combination in a box strapping machine, of means for supporting a box in strapping position, means including a feed wheel for feeding a strap to said position, means for gripping the end of a strap extended around a box in said position, a feed shaft on which said feed wheel is rotatably mounted, a countershaft connected to drive said feed wheel, a tensioning device for drawing said strap taut around the box after it is held

by said gripping means, a cam shaft connected to be driven by said feed shaft, means including cams fixed on said cam shaft for controlling the operation of said gripping means and said tensioning device, power actuated means, means for connecting said power actuated means to said countershaft to drive said feed wheel, means for automatically stopping the rotation of said countershaft, and means for automatically connecting said power actuated means to said feed shaft to rotate said cam shaft.

23. The combination in a box strapping machine, of means for supporting a box in strapping position, means including a feed wheel for feeding a strap to said position, means for gripping the end of a strap extended around a box in said position, a feed shaft on which said feed wheel is rotatably mounted, a countershaft connected to drive said feed wheel, a tensioning device for drawing said strap taut around the box after it is held by said gripping means, a second gripping means for holding the supply portion of the strap after it has been drawn taut by said tensioning device, a cam shaft connected to be driven by said feed shaft, means including cams fixed on said cam shaft for controlling the operation of said gripping means and said tensioning device, power actuated means, means for connecting said power actuated means to said countershaft to drive said feed wheel, and means for connecting said power actuated means to said feed shaft to actuate said cam shaft.

24. The combination in a box strapping machine, of means for supporting a box in strapping position, means including a feed wheel for feeding a strap to said position, means for gripping the end of a strap extended around a box in said position, a feed shaft on which said feed wheel is rotatably mounted, a countershaft connected to drive said feed wheel, a tensioning device for drawing said strap taut around the box after it is held by said gripping means, a second gripping means for holding the supply portion of the strap after it has been drawn taut by said tensioning device, a shearing device for cutting the supply portion of the strap after it is held by said second gripping means, means for welding the strap ends together, a cam shaft connected to be driven by said feed shaft, means including cams fixed on said cam shaft for operating said gripping means, said tensioning device, said shearing device and said welding means in predetermined sequential relation, power actuated means, means for connecting said power actuated means to said feed shaft to actuate said cam shaft, and means for connecting said power actuated means to said countershaft to drive said feed wheel.

25. The combination in a box strapping machine, of means for supporting a box in strapping position, means including a feed wheel for feeding a strap to said position, means for gripping the end of a strap extended around a box in said position, a feed shaft on which said feed wheel is rotatably mounted, a countershaft connected to drive said feed wheel, a tensioning device for drawing said strap taut around the box after it is held by said gripping means, a second gripping means for holding the supply portion of the strap after it has been drawn taut by said tensioning device, a shearing device for cutting the supply portion of the strap after it is held by said second gripping means, means for welding the strap ends together, a cam shaft connected to be driven by said feed shaft, means including cams fixed on said cam shaft for operating said gripping means, said tensioning device, said shearing device and said welding means in predetermined sequential relation, power actuated means, means for connecting said power actuated means to said feed shaft to actuate said cam shaft, means for connecting said power actuated means to said countershaft to drive said feed wheel, and means for stopping the rotation of said feed wheel and reversing the direction of its rotation to take up the slack in the strap extending around the box in advance of the operation of said tensioning device.

26. The combination in a box strapping machine, of a table for supporting a box in strapping position, a pair of spaced gripping plates mounted in said table beneath said position, a pair of spaced welding points mounted between said plates, a pair of gripping dogs each adapted to cooperate with one of said plates to grip the strap, a welding head adapted to cooperate with said points to unite portions of said strap, and means movable to and from a position between said gripping dogs for guiding said strap.

27. The combination in a box strapping machine, of a table for supporting a box in strapping position, a pair of spaced gripping plates mounted in said table beneath said position, a pair of spaced welding points mounted between said plates, a pair of gripping dogs each adapted to cooperate with one of said plates to grip the strap, means movable to and from a position between said gripping dogs for guiding said strap, and welding means operative when said guiding means is retracted for cooperating with said welding points to form a joint in the strap between said gripping dogs.

28. The combination in a box strapping machine, of a table for supporting a box in strapping position, a pair of spaced gripping plates mounted in said table beneath said position, a pair of gripping dogs each adapted to cooperate with one of said plates to grip the strap, one of said gripping dogs having a slot through which the strap passes before being extended around the box and being adapted to grip the end of the strap after it has been so extended, the other gripping dog being adapted to grip the supply portion of the strap after it has been so extended, and means for actuating said gripping dogs to cause them to force the strap against said plates with resilient pressure.

29. The combination in a box strapping machine, of a table for supporting a box in strapping position, a pair of spaced gripping plates mounted in said table beneath said position, a pair of spaced welding points mounted between said plates, a pair of gripping dogs each adapted to cooperate with one of said plates to grip the strap, one of said gripping dogs having a slot through which the strap passes before being extended around the box and being adapted to grip the end of the strap after it has been so extended, the other gripping dog being adapted to grip the supply portion of the strap after it has been so extended, means for guiding the end of the strap to overlap the supply portion thereof between said dogs when the strap is so extended around the box, means for drawing the strap taut around the box, means for cutting off the supply portion, and means for welding the overlapping portions together.

30. The combination in a box strapping machine, of means for holding the end of a strap looped around a box, a pivotally mounted frame having a gripping surface to coat with the portion of said strap leading from a source of supply, a gripping dog pivotally mounted on said frame to press said strap against said surface, a stationary cam having an inclined cam surface, a tripping member mounted on said gripping dog and arranged to coat with said inclined cam surface to control the engagement of said gripping dog with said strap when said frame is tilted about its pivot, a driven cam shaft, a rotary cam fixed on said shaft for tilting said frame to move said dog between two extreme positions, and fluid pressure operated means for pressing said frame against said rotary cam with a resilient pressure and thereby actuating said frame to set up a predetermined tension in said strap at a certain point in the rotation of said rotary cam.

31. The combination in a box strapping machine, of means for holding the end of a strap looped around a box, a pivotally mounted frame having a gripping surface to coat with the portion of said strap leading from a source of supply, a gripping dog pivotally mounted on said frame to press said strap against said surface, a stationary cam having an inclined cam surface, a trip-

ping member mounted on said gripping dog and arranged to coat with said inclined cam surface to control the engagement of said gripping dog with said strap when said frame is tilted about its pivot, a driven cam shaft, a rotary cam fixed on said shaft for tilting said frame to move said dog between two extreme positions, and a torsion shaft connected to said frame and adapted to be twisted by the tilting of said frame to cause said frame to bear on said rotary cam with a resilient pressure by which said frame is actuated to set up a predetermined tension in said strap when said rotary cam reaches a predetermined point in its rotation.

32. The combination in a box strapping machine including means for clamping a metal strap disposed about a box, of a feed wheel shaft, a feed wheel on said shaft for feeding the strap toward the box, a cam shaft for operating said clamping means, power means for alternately rotating said feed wheel shaft and said cam shaft, and electrical control means actuated by said feed wheel shaft for initiating the rotation of said cam shaft when said feed wheel shaft has stopped rotating.

33. The combination in a box strapping machine including means for clamping a metal strap disposed about a box, of a feed wheel shaft, a feed wheel on said shaft for feeding the strap toward the box, a cam shaft for operating said clamping means, and means including a rotary switch driven by said feed wheel shaft for controlling the rotation of said cam shaft, said rotary switch comprising two sets of electrical contacts, one set of said contacts being closed when said feed wheel shaft is idle and the other set of said contacts being closed when said feed wheel shaft is rotated, whereby said cam shaft is prevented from rotating when said feed wheel shaft is rotated.

34. The combination in a box strapping machine of a power driven cam shaft, relatively stationary means for holding one end of a strap, a pivotally mounted frame, a cam mounted on said shaft for tilting said frame between two positions, a strap gripping device attached to said frame for gripping the strap at a place thereon remote from the end of the strap whereby to tension the strap upon tilting movement of said frame from one of said positions toward the other, and resilient means for holding said frame in engagement with said cam.

35. The combination in a box strapping machine of means for holding one end of a strap, a pivotally mounted frame, a strap gripping device carried by said frame for gripping the other end of said strap, a power driven cam shaft, a cam mounted on said shaft for tilting said frame and thereby moving said gripping device between two extreme positions, and fluid pressure operated means for holding said frame in engagement with said cam, whereby the rotation of said cam actuates said gripping device to tension said strap.

36. The combination in a box strapping machine of a power driven cam shaft, relatively stationary cam means for holding one end of a strap, a pivotally mounted frame, a cam mounted on said shaft for tilting said frame, a strap gripping device attached to said frame for gripping the strap at a place thereon remote from the end of the strap whereby to tension the strap upon tilting movement of said frame, and fluid pressure operated means for pressing said frame against said cam.

37. The combination in a box strapping machine of a power driven shaft, relatively stationary means for holding one end of a strap, a rotary cam on said shaft, a pivotally mounted frame arranged to be actuated by said cam, a strap gripping device attached to said frame for gripping the strap at a place thereon remote from the end of the strap, a torsion bar connected to said frame and adapted to press said frame against said cam, and means for twisting said torsion bar whereby said frame is tilted by the rotation of said cam to tension the strap.

UNITED STATES PATENT OFFICE
CERTIFICATE OF CORRECTION

April 21, 1959

Patent No. 2,882,814

Alvin L. Winkler et al.

It is hereby certified that error appears in the printed specification of the above numbered patent requiring correction and that the said Letters Patent should read as corrected below.

Column 28, line 21, after "guiding means" insert -- from the vicinity of said end of said strap --; line 59, for "strapping" read -- strapping --; column 32, line 56, after "stationary" strike out "cam".

Signed and sealed this 1st day of September 1959.

(SEAL)
